(57) **CLAIM**

The ornamental design for a magnetic block set, as shown and described.

DESCRIPTION

FIG. 1 is a perspective view of a square magnetic block of the magnetic block set showing my new design;

FIG. 2 is a front elevation view thereof, with the rear elevation view a mirror image of the front;

FIG. 3 is a right elevation view thereof, with the left elevation view a mirror image of the left;

FIG. 4 is a top view thereof, with the bottom view a mirror image of the top;

FIG. 5 is a perspective view of a rectangular magnetic block of the magnetic block set showing my new design;

FIG. 6 is a front elevation view thereof, with the rear elevation view a mirror image of the front;

FIG. 7 is a right elevation view thereof, with the left elevation view a mirror image of the left;

FIG. 8 is a top view thereof, with the bottom view a mirror image of the top;

FIG. 9 is a perspective view of a right triangular magnetic block of the magnetic block set showing my new design;

FIG. 10 is a front elevation view thereof;

FIG. 11 is a rear elevation view thereof;

FIG. 12 is a right elevation view thereof;

FIG. 13 is a left elevation view thereof;

FIG. 14 is a top view thereof;

FIG. 15 is a bottom view thereof;

FIG. 16 is a perspective view of an isosceles triangular magnetic block of the magnetic block set showing my new design;

FIG. 17 is a front elevation view thereof, with the rear elevation view a mirror image of the front;

FIG. 18 is a right elevation view thereof, with the left elevation view a mirror image of the left;

FIG. 19 is a top view thereof;

FIG. 20 is a bottom view thereof;

(Continued)

FIG. 21 is a perspective view of an equilateral triangular magnetic block of the magnetic block set showing my new design;
 FIG. 22 is a front elevation view thereof;
 FIG. 23 is a rear elevation view thereof;
 FIG. 24 is a right elevation view thereof, with the left elevation view a mirror image of the left;
 FIG. 25 is a top view thereof;
 FIG. 26 is a bottom view thereof;
 FIG. 27 is a perspective view of a trapezoidal magnetic block of the magnetic block set showing my new design;
 FIG. 28 is a front elevation view thereof, with the rear elevation view a mirror image of the front;
 FIG. 29 is a right elevation view thereof, with the left elevation view a mirror image of the left;
 FIG. 30 is a top view thereof; and,
 FIG. 31 is a bottom view thereof.
 The claim is directed to the collective appearance of the magnetic block set as shown in FIGS. 1-31.
